UNITED STATES PATENT OFFICE

EDGAR F. HATHAWAY, OF WELLESLEY, AND WALTER BIXBY, OF BOSTON,
MASSACHUSETTS

TUBE FRAME

Application filed October 4, 1930. Serial No. 486,361.

This invention relates to tube frames such as are used for weaving Axminster carpets and the like and is intended to provide a reliable and convenient means for securing the tuft-receiving and guiding tubes to the carrier bar, which forms, so to speak, the backbone of the tube frame.

In previous tube frame constructions, such as shown in United States Patents No. 1,519,978 and No. 1,545,809, we have proposed securing the individual tuft tubes side by side in a slotted tube spacing and attaching strip of pressed metal, in which such tube-attaching or tube-carrying strips were removably fastened to the bar by screws and such constructions have gone into extensive commercial use. However, the constant and rough jarring to which the tube frames are subjected in Axminster looms, as they travel through a devious route with the carrier chains to which they are suspended, results occasionally in jarring loose some of the parts with the result that a loose part may drop into the loom and cause serious damage or injury.

It is the object of the present invention to provide a tube-attaching construction which, though subject to loosening of the parts, prevents the anchoring screws from dropping out of the tube frame into the loom. A further feature of the invention consists in the construction and arrangement by which the tuft tubes are grouped on short individual sections of the carrier strip, while a continuous guard strip is provided projecting outward beyond the rear end edges of the tuft tubes and avoiding leaving any crack or joint between adjacent sections of the carrier strip in which thread or yarn can catch as it is drawn from the yarn spool into the appropriate tuft tubes or guides.

These and other features of the invention will be described in the following specification and will be defined in the claims hereto annexed.

In the accompanying drawing we have illustrated constructions embodying the principles of this invention, in which

Fig. 1 is a perspective view showing the carrier bar with tuft tubes, attaching strip

sections and a guard member assembled in operative relation thereto.

Fig. 2 is a detail view showing one section of an attaching strip with tuft tubes secured thereto, part of them being broken away to show the rearwardly projecting fastening screws.

Fig. 3 is an end elevation of the tuft tubes and end attaching strip shown in Fig. 2.

Fig. 4 is a front view of the guard member for protecting the yarn tufts as they pass into the individual tuft tubes.

Fig. 5 is an end view of the guard member shown in Fig. 4.

Fig. 6 is a cross sectional view showing the guard member, the tube attaching strip and the fastening means in proper assembled position on the carrier bar.

Figs. 7 and 8 are plan views and end elevations, respectively, of a modified construction corresponding to Fig. 4 and Fig. 5.

Fig. 9 is a cross sectional view of the modified construction corresponding to Fig. 6.

Fig. 10 is a perspective view showing the modified form of attaching strip and guard member in assembled relation to the carrier bar.

In the practice of our invention according to the form illustrated in the drawing, the carrier bar, which is of tubular or hollow construction, extends the full length of the tube frame of which it forms, in effect, the backbone and is secured at its opposite ends to the suspension hangers, which suspend the tube frame from the carrier chains and which carry the yarn spool, all in well known manner as illustrated in Bixby Patent No. 1,545,809 above mentioned.

Preferably the parallel tuft tubes, which receive and guide the yarn tufts, are arranged in groups, each group being attached transversely to a longitudinal attaching strip 2, preferably of angular form, to the front face of which the individual tubes 3 are soldered or spot-welded. A number of such sections placed end to end along the carrier bar in proper position thereon constitute the entire series of tuft tubes for the tube frame, which may be of various lengths, according to the width of rug or carpet to be woven.

Each strip section 2, at two points at least, has punched out apertures surrounded by offset annular or tubular flanges 5 which project from the rear face of the attaching strip, so as to register with corresponding apertures formed in the front wall of the carrier bar. These offset annular flanges not only form a means for accurately and reliably positioning the attaching strip on the carrier bar, but they also form a frusto-conical seat for the reception of a tapered head screw 6, which is inserted through the aperture so as to project rearwardly perpendicular to the plane of the attaching strip, in which position it is spot-welded or soldered securely to the strip so as to become to all intents and purposes an integral part thereof.

Opposite the screw receiving aperture of the carrier bar 1 is formed an aligned aperture 7, in which is inserted the anchoring member which in this case comprises a tubular internally threaded screw 8 provided with an intermediate enlarged shoulder 8^a spaced some distance from the head of the screw and dimensioned to slightly exceed the diameter of the aperture 7 through which the anchoring member or female screw is inserted.

This diameter is only a few thousandths larger than the diameter of the aperture 7 so that the screw can be forced through the aperture under pressure, since the excess diameter is small enough to allow the metal to yield sufficiently to allow the shoulder to pass while returning to normal size after the shoulder has been forced through, thereby preventing the anchoring member from dropping out of the carrier bar. The shoulder 8^a is located sufficiently near the head of the screw 8 so that its inner end stands in overlapped relation to the attaching screw 6.

While the attaching strips are made in sections or short lengths, each carrying an individual group of tuft tubes, the guard strip 10 is preferably continuous or one-piece throughout the length of the attaching strip. This guard piece comprises a flat body portion 10 adapted to underlap the upper edge of the attaching strip itself formed at its upper portion with a struck-up rib or shoulder 10^a which projects far enough forwardly of the rear end edges of the individual tube frames to prevent the tuft yarn from catching against these thin edges.

Instead of making the tube-carrying and attaching strip and the guard member in separate pieces, as above described, these two members may be made in a single integral piece.

As shown in Fig. 7 and Fig. 8 the attaching strip 11 is of angular form to embrace the lower corner of the carrier bar as in the preferred form above described and, at its upper end is formed with a projecting hollow rib 11^a which acts as a guard to prevent the tuft

yarn from catching against the thin rear edge of the back wall of the individual tuft tube. The intermediate portion of the carrier strip 11 is provided with a punched out aperture forming the rearwardly offset annular flange 11^b for engaging the screw-receiving aperture of the front wall and also to form a seat for the flared head of the screw 6, which is soldered or spot-welded therein in the manner and for the purpose above described.

As the tuft tube units in the sectional construction are attached to strips only two or three inches long, it is a very simple matter, when any of the tubes are injured, to unscrew the anchoring screws at the back of the carrier bar, remove the strip containing the injured tuft tubes, and quickly replace it with another similar unit, which is similarly anchored in place. This may be done without even taking the tuft tube out of the loom and does not require the service of a skilled mechanic.

Moreover, it is impossible for the anchoring member to drop out into the loom and cause damage, even should it become loosened by the constant jarring. Once inserted, the anchoring members are always in place for use for anchoring the fastening screws that project from and are integrally united with each tuft tube unit. The annular lip or flange surrounding each fastening screw and registering with the adjacent aperture in the carrier bar secures exact alignment and prevents displacement under the tension of the anchoring screw or member.

What we claim is:

1. In a tube frame the combination with a hollow carrier bar provided with aligned apertures in its front and rear walls, a tube carrying strip to which are securely united in parallelism a plurality of tuft tubes, said strip being provided with a rearwardly projecting non-rotatable screw integrally united with the strip arranged to pass through the aperture in the front wall, and means projecting through the aperture in the rear wall of the bar having threaded anchoring engagement with said screw to anchor the tube carrying strip in place.

2. In a tube frame the combination with a hollow carrier bar provided with aligned apertures in its front and rear walls, a tube carrying strip to which are securely united in parallelism a plurality of tuft tubes, said strip being provided with a rearwardly projecting non-rotatable screw integrally united with the strip arranged to pass through the aperture in the front wall, anchoring means projecting through the aperture in the rear wall of the bar to have threaded engagement with said screw, and means for preventing said anchoring screw falling out of its containing aperture when loosened from said screw.

3. In a tube frame the combination with a tubular carrier bar of a tuft tube carrying strip to which a series of transverse tuft tubes are secured in parallelism, a portion 5 of the strip beneath the superimposed tuft tubes being formed with a countersunk annular flange adapted to register with a corresponding aperture in the adjacent wall of the carrier bar, a non-rotatable fastening screw whose head is seated in the countersunk flange and integrally united therewith, and anchoring means projecting through the rear wall of said carrier bar to form threaded anchoring engagement with said 10 fastening screw.
4. In a tube frame the combination with a tubular carrier bar, a tuft tube carrier strip to which a series of transverse tuft tubes are secured in parallelism, portions of 20 the strip beneath the attached tuft tubes formed with countersunk annular flanges adapted to register with corresponding apertures in the adjacent wall of the carrier bar, non-rotatable fastening screws whose heads 25 are seated in and integrally united with the respective countersunk flanges, and tubular internally threaded anchoring members inserted through apertures in the rear wall of the carrier to engage and firmly anchor the 30 fastening screws in the carrier bar.
5. In a tube frame construction, the combination with a carrier bar, a longitudinal tube carrying strip to which are permanently secured a plurality of transverse tuft tubes, means for securing said carrier strip detachably to the carrier bar comprising a threaded member rigidly secured to said strip and projecting rearwardly therefrom to extend into the interior of the carrier bar, a coacting 40 threaded member inserted through an aperture in the rear of the carrier bar and provided with a shoulder intermediate of its ends of larger diameter than the diameter of the aperture through which it is inserted.
6. In a tube frame construction, the combination with a hollow carrier bar having aligned perforations in its front and rear walls, a tube carrying strip provided with an integrally united rearwardly projecting 50 attaching member arranged to be passed through the aperture of the front wall, a rotatable anchoring member adapted to be inserted through the aperture in the rear wall to have threaded anchoring engagement with said screw, said anchoring member being provided with a shoulder slightly larger than the diameter of the aperture in the rear wall to permit its being forced through said aperture while preventing its 55 falling out through said aperture, the screw and the anchoring member being dimensioned in length to retain threaded engagement with said shoulder engages the edge of the aperture in the rear wall.
7. A replaceable tuft tube unit for a tube 60
- frame, embracing in its construction a longitudinal strip provided with screw-receiving apertures whose edges are offset to form annular flanges, non-rotatable attaching screws seated in and integrally united with said flanges, said attaching screws being spaced longitudinally to penetrate corresponding apertures in the carrier bar of a tube frame. 70
8. In a tube frame the combination with a hollow carrier bar, of a longitudinal tube carrying and attaching strip having screw-receiving apertures whose edges are upset to form rearwardly extending annular guide and positioning flanges, non-rotatable fastening screws integrally united with said flanges 80 to project into the carrier bar and engage anchoring members carried thereby, said tube carrying strip being provided with a forwardly projecting yarn guarding member arranged to overhang the intake ends 85 of the tubes.
9. In a tube frame the combination with a carrier bar, a series of end to end tube carrying and attaching strips separately and detachably secured to said bar, a continuous guard strip arranged to underlie a plurality of the tube carrying strips and provided with a forwardly projecting rib arranged to overhang the intake ends of the tubes carried by said strips and guide the yarn tufts 90 into the individual tubes.
- In witness whereof, we have subscribed the above specification.
